(57) **CLAIM**

The ornamental design for a mouth stick, as shown and
described.

DESCRIPTION

FIG. 1 is a top, front, side perspective view of a mouth stick
showing our new design;

FIG. 2 is an enlarged front end view thereof;

FIG. 3 is a top view thereof;

FIG. 4 is a side view thereof;

FIG. 5 is a bottom view thereof; and,

FIG. 6 is an enlarged rear end view thereof.

The broken lines shown on the mouth stick form no part of the
claimed design.
